UNITED STATES PATENT OFFICE.

ABRAM L. SHUTTER, OF WEST HAVEN, CONNECTICUT, ASSIGNOR TO JAMES GRAHAM & CO., OF NEW HAVEN, CONNECTICUT, A FIRM COMPOSED OF SAID SHUTTER AND CHARLES E. GRAHAM.

HOOD FASTENER.

Application filed November 28, 1921. Serial No. 518,414.

To all whom it may concern:

Be it known that I, ABRAM L. SHUTTER, a citizen of the United States, residing at West Haven, in the county of New Haven 5 and State of Connecticut, have invented a new and useful Improvement in Hood Fasteners; and I do hereby declare the following, when taken in connection with the accompanying drawings and the characters of 10 reference marked thereon, to be a full, clear, and exact description of the same, and which said drawings constitute part of this application, and represent, in—

Fig. 1 a side view, partly in section, of 15 a hood fastener constructed in accordance with my invention.

Fig. 2 a sectional view on the line 2—2 of Figure 1.

Fig. 3 a plan view of the base detached. 20 Fig. 4 a side view of the post detached.

Fig. 5 a side view of the latch detached. 25 My invention relates to improvement in hood fasteners, such as are employed for fastening the hoods of automobiles. The object of this invention is to construct a device the parts of which may be readily cast, and which do not require any machine work in finishing and which will provide a secure fastening device for the hoods of 30 automobile engines, and the invention consists in the construction as hereinafter described and particularly recited in the claims.

In carrying out my invention, I employ, a 35 base 10 adapted to be secured to the frame of an automobile adjacent to the sides of the hood. This base is formed from a single casting and provided with an upwardly-projecting plate 11, which forms a bearing 40 for the lower edge of an ordinary hood 12, which is also provided, above its lower edge, with a loop 13. The base is formed in its under face with a chamber 14 and with a slot 15 to give clearance for a post 16, which 45 is provided near its lower end with a transverse opening 17 for the passage of a locking-pin 18. This post is provided with a head 19. Around the post is a latch 20 formed from a single casting and provided 50 with a locking-hook 21 adapted to engage with the loop 13 and at the opposite side with a finger-grip 22. This latch has a chamber 23 corresponding substantially in diameter to the head 19, and at its lower end

with a hole 24 corresponding substantially 55 in diameter to the post 16, so as to form a shoulder 25 upon which is seated a spring 26, the other end of which bears against the head 19, the tendency of the spring being to depress the latch. 60

The parts thus described are readily cast and do not require any machining to complete them. The device is assembled by inserting the spring 26 into the chamber 23, then passing the post downward through 65 the latch and into the base and forcing the pin downward against the action of the spring 26 until the lower end projects sufficiently below the base, as indicated in broken lines in Figure 2, to permit the insertion of the locking-pin 18. In operation, the latch is gripped and a firm hold is secured by means of the finger-piece 22, and raised against the force of the spring 26 until the hook 21 engages with the loop 13. 70 The device is then released and the spring forces the latch downward and holds it firmly in engagement with the hood. In releasing the hook, the latch is raised as before, and, owing to the slot 15, the latch and 75 post may rock on the base. This construction provides a hood fastener of attractive appearance and effective in use.

The plate 11 provides a firm bearing for the hook, which is drawn against it by the 80 latch, so that rattling is avoided.

I claim:

1. A hood fastener, comprising a latch formed with a locking-hook and having a tubular chamber open at its upper end and 90 formed with an integral spring seat, and a hole at its lower end, a headed post entering said chamber and formed with a transverse hole near its lower end, a spring around said post within said chamber, a base 95 formed in its under side with a recess, and with a slot intersecting said recess, into which the post extends, and a pin extending through said post and seated in said recess. 100

2. A hood fastener, comprising a latch formed with a locking-hook and having a tubular chamber open at its upper end and 105 formed with an integral spring seat, and a hole at its lower end, a headed post entering said chamber and formed with a transverse hole near its lower end, a spring around said post within said chamber, a

base formed in its under side with a recess and having an upwardly-projecting integral plate, and with a slot intersecting said recess, into which the post extends, and a 5 pin extending through said post and seated in said recess.

In testimony whereof, I have signed this

specification in the presence of two subscribing witnesses.

ABRAM L. SHUTTER.
